ABSTRACT: Elemental sulfur is introduced into a cell containing an electrolyte of the composition $KF \cdot nHF$ (wherein $n=0.9$ to 3), and electrolysis is carried out with use of a carbon anode to produce sulfur hexafluoride.

PROCESS FOR THE MANUFACTURE OF SULFUR HEXAFLUORIDE

BACKGROUND OF THE INVENTION

This invention relates to a process for the production of sulfur hexafluoride. More particularly, the invention relates to a process for producing sulfur hexafluoride by electrolysis.

DESCRIPTION OF THE PRIOR ART

It is well known to use sulfur hexafluoride as a gaseous insulating medium for sealed electrical apparatus such as transformers.

In the hitherto-known methods for the manufacture of sulfur hexafluoride, sulfur, sulfur dichloride, sulfur monochloride, carbon disulfide or hydrogen sulfide is introduced into anhydrous hydrogen fluoride and nickel anodes are used to effect the necessary electrolysis (See the specifications of U.S. Pat. Nos. 3,345,277 and 2,717,235).

Anhydrous hydrogen fluoride has a boiling point of 19° C. and the known methods require low-temperature operation at -30° C. and 0° C.

Furthermore, because of the poor electric conductivity of anhydrous hydrogen fluoride, it is necessary to employ a conductive additive, for example, potassium fluoride. The potassium fluoride causes considerable dissolution of the nickel anode and an increase in current density accelerates this dissolution, causing a substantial loss of nickel.

BRIEF SUMMARY OF THE INVENTION

It is an object of this invention to provide an electrolytic process for producing pure sulfur hexafluoride in commercial quantities from elemental sulfur and a $KF\cdot nHF$ electrolyte.

Another object is to provide an electrolytic process for producing sulfur hexafluoride in a high yield without a substantial loss of the anode.

Other objects and advantages of the present invention will become apparent to those skilled in the art from the following description and disclosure.

DETAILED DESCRIPTION OF THE INVENTION, INCLUDING PREFERRED EMBODIMENTS

It has been found that electrolysis of an electrolyte of $KF\cdot nHF$ (wherein n equals 0.9 to 3.0) in the presence of elemental sulfur and with a carbon anode yields commercial quantities of sulfur hexafluoride refrigeration equipment and substantially without dissolution of the anode.

In the present invention, a mixture of potassium fluoride and hydrogen fluoride in a mole ratio of HF:KF of 0.9:1 to 3:1 does not liberate substantial amounts of hydrogen fluoride vapor near its melting point and has such a high electric conductivity that the voltage necessary for electrolysis may be comparatively low.

A carbon anode is substantially immune to dissolution in the presence of potassium fluoride.

If the HF:KF ratio is less than 0.9:1, the vapor pressure of hydrogen fluoride over the mixture will be too high and the melting point of the mixture will also be too high for a commercially practical process. Exceeding the limit of 3:1 will also cause a significant increase in the vapor pressure of hydrogen fluoride over the mixture and loss of hydrogen fluoride.

An electrolyte wherein the ratio of HF to KF is 1.8 to 2.2 has a particularly favorable melting point and vapor pressure.

To carry the invention into practice, elemental sulfur and the electrolyte are introduced into an electrolytic cell. The electrolyte is first fed into the cell, and is followed by elemental sulfur added to the anolyte. Hydrogen fluoride gas is fed to the electrolyte to maintain the original composition.

Elemental sulfur may be used in the solid form, such as colloidal sulfur, powdery sulfur or granular sulfur, or in the molten state. Elemental sulfur is substantially insoluble in the $KF\cdot nHF$ melt. The electrolyte temperature is selected between the melting point of the mixture and the melting point plus 50° C.

If the mixture is heated to an excessively high temperature, hydrogen fluoride is evaporated. A temperature of 80° C. to 130° C. is preferred when a mixture of 1.8 KF to 2.2 HF is to be melted.

At a voltage of 5 to 15 volts and a current density of 0.5 to 25 a./dm.², sulfur hexafluoride is produced at a current efficiency of about 40 to 92 percent.

At 6 to 12 volts and a current density of 4 to 12 a./dm.² based on the effective anode surface, the process of this invention gives sulfur hexafluoride continuously at a current efficiency of 65 to 92 percent.

At a voltage of less than 5 volts and a current density below 0.5 a./dm.², substantially no sulfur hexafluoride will be produced. The output of lower fluorinated sulfur compounds is increased and a larger anode area will have to be provided. At a voltage above 15 volts and a current density beyond 25 a./dm.², there may be formed an insulating fluorinated carbon layer on the surface of the carbon anode and make the electrolysis substantially impossible.

A small amount, for example, 1 to 3 weight percent of the $KF\cdot nHF$ mixture, of lithium fluoride, aluminum fluoride, nickel fluoride, or sodium fluoride, is effective in preventing the coating of the anode at not more than 25 a./dm.².

The present invention will be further described in the following examples which are illustrative and by no means limitative thereof. In those examples, two different electrolytic cells were employed.

Type I Electrolytic Cell

This electrolytic cell consists of a cylindrical vessel made of iron, 240 mm. in diameter and 550 mm. in depth, and an iron cover. The vessel serves as a cathode. In the center of the cover, there is provided an anode of amorphous carbon, 100 mm. in diameter, 480 mm. in length and 12 dm.² in effective surface area. The cover is also provided, about the carbon anode, with a cylindrical skirt of iron, 160 mm. in diameter, 150 mm. in length and 2 mm. in thickness, for separating the gases evolved from both electrodes.

The cover is further provided with holes through which elemental sulfur is fed into the anode chamber.

Type II

The electrolytic cell consists of a cylindrical vessel of iron, 100 mm. in diameter and 150 mm. in depth, and a cell cover of iron. The vessel serves as a cathode. In the center of the cover, there is provided an anode of amorphous carbon, 40 mm. in diameter, 100 mm. in length and 1.1 dm.² in effective surface area. The cover is also provided, about the carbon anode, with a cylindrical skirt of iron for separating the gas evolved from the electrodes. The skirt measures 70 mm. in diameter, 60 mm. in length and 1 mm. in thickness. The cover is further provided with a pipe for admitting elemental sulfur to the anode chamber. The cell is provided, at the bottom, with a pipe for admitting an inert gas and for thereby sweeping the sulfur hexafluoride from the cell.

Acid potassium fluoride (KHF_2) and anhydrous fluoride gas were admitted into the cell to prepare an electrolyte. The electrolyte was held at a constant temperature (about 90° C.), and in order to remove water from the electrolyte, electrolysis was carried out for 24 hours at a low current density (0.1-0.3 a./dm.²). After this preliminary electrolysis, elemental sulfur was admitted into the anode chamber, an inert gas was introduced, and the product of electrolysis was withdrawn thereby as a gas from the electrolytic cell. The gas contained a small amount of hydrogen fluoride and was passed through a tube packed with sodium fluoride pellets.

It was washed free of byproducts, SO_2F_2 , SOF_2 , etc., with water and, then, with aqueous alkali solutions. The traces of S_2F_{10} , $S_2F_{10}O$ and other compounds occurring in this gas were thermally decomposed and, finally, the gas was passed through an alumina-filled tube to remove any residual trace impurities.

The final gas was sulfur hexafluoride, which was analyzed by gas chromatography and by infrared and mass spectroscopic methods.

Control Example

In the cell of type II, the carbon anode was replaced with a Ni plate anode, and electrolysis was carried out in the following manner. To the anode chamber containing 1.6 kg. of KF-2HF melt, 15 g. colloidal sulfur was added. With the electrolyte being maintained at a temperature of 90° C., electrolysis was conducted at a current density of 8.14 a./dm.². The cell voltage was 5.9 volts. The gas evolved from the anode chamber contained such compounds as SF₆, SOF₂, SO₂F₂, S₂F₁₀, etc.

After 3 hours of electrolysis, the nickel anode was removed from the cell and examined for weight loss. It was dissolved at a rate of 3.8 g./100 ampere-hours. Electrolysis was further continued, whereupon the formation of a sludge in the cell bottom was observed.

EXAMPLE 1 (CELL TYPE I)

Into the electrolytic cell, 41.50 kg. of an electrolyte of KF-2.15HF containing 1.1 weight percent of LiF was admitted, and 100 g. of colloidal sulfur was introduced into the anode chamber. Electrolysis was carried out at an electrolyte temperature of 98° C. and a current density of 5.0 a./dm.². The cell voltage was 8.93 volts. After 3 hours of electrolysis, the gas evolved in the anode chamber was analyzed. The result was: SF₆, 93%; SO₂F₂, 1%; SOF₂+SF₄<1%; S₂F₁₀, 1%; S₂F₁₀D<0.5%; CO₂, 1%; F₂, 1%; CF₄, 0.5%; air, 0.5%. On further electrolysis, the amounts of SOF₂, SO₂F₂, CO₂, and S₂F₁₀O became traces. After purification, the SF₆ was 99 percent pure, containing 0.5CF₄ and 0.5% air. The current efficiency of sulfur hexafluoride formation was 92 percent. The conversion of hydrogen fluoride to sulfur hexafluoride was in excess of 95 percent.

EXAMPLE 2 (CELL TYPE II)

Into the electrolytic cell, 1.6 kg. of an electrolyte of KF-2HF was admitted, and 15 g. colloidal sulfur was introduced into the anode chamber. With the introduction of nitrogen gas at a rate of 21N ml./min., electrolysis was conducted at an electrolyte temperature of 98° C. and a current density of 8.9 a./dm.². The initial cell voltage was 7.60 volts. The concentration of sulfur hexafluoride in the gas evolved from the anode chamber was 48 percent. The balance of the gas was predominantly nitrogen and, to a minor part, fluorine. The current efficiency of sulfur hexafluoride formation was 85 percent. During 3 hours of electrolysis, the carbon anode suffered substantially no dissolution.

EXAMPLE 3 (CELL TYPE II)

Into the electrolytic cell, 1.6 kg. of an electrolyte of KF-2HF was admitted, and 15 g. colloidal sulfur was introduced into the anode chamber. With the introduction of nitrogen gas at a rate of 21N ml./min., electrolysis was carried out at an electrolyte temperature of 108° C. and a current density of 4.1 a./dm.². The initial cell voltage was 6.75 volts and 6.64 volts

after 4 hours. The current efficiency of sulfur hexafluoride formation was 68 percent.

EXAMPLE 4 (CELL TYPE II)

5 Into the electrolytic cell, 1.6 kg. of an electrolyte of KF-2HF was admitted, and 15 g. sulfur was introduced into the anode chamber. With the introduction of nitrogen gas at a rate of 14.5N ml./min., electrolysis was conducted at an electrolyte temperature of 108° C. and a current density of 0.5 a./dm.². The cell voltage was 5.53 volts at the start of electrolysis, while it was 5.54 after 5 hours. The current efficiency of sulfur hexafluoride formation was 45 percent.

EXAMPLE 5 (CELL TYPE II)

15 Into the electrolytic cell, 1.6 kg. of an electrolyte of KF-1.8HF was admitted, and 15 g. sulfur was introduced into the anode chamber. With the introduction of nitrogen gas at a rate of 20N ml./min., electrolysis was conducted at an electrolyte temperature of 125° C. and a current density of 1.4 a./dm.². The cell voltage was 5.85 volts at the start of electrolysis, and 5.81 volts after 5 hours. The current efficiency of sulfur hexafluoride formation increased with time and reached 63 percent in 5 hours.

We claim:

- 20 1. In a process of manufacturing sulfur hexafluoride by electrolysis between an anode and a cathode of an electrolyte essentially consisting of potassium and hydrogen fluoride and containing elemental sulfur in the anolyte, and by recovery of the hexafluoride formed from the electrolyte, the improvement which comprises:
  - a. the mole ratio of HF to KF in said electrolyte being 0.9:1 to 3:1; and
  - b. the effective surface of the anode essentially consisting of carbon.
- 25 2. In a process as set forth in claim 1, said carbon being amorphous carbon.
- 30 3. In a process as set forth in claim 1, the temperature of said electrolyte being above the melting point thereof by not more than 50° C. and the anode current density being between 0.5 2 and 25 a./dm.².
- 35 4. In a process as set forth in claim 3, the voltage between said anode and said cathode being 5 to 15 volts.
- 40 5. In a process as set forth in claim 4, said current density being 4 to 12 a./dm.², and said voltage being 6 to 12 volts.
- 45 6. In a process as set forth in claim 1, said mole ratio being 1.8:1 to 2.2:1.
- 50 7. In a process as set forth in claim 6, the temperature of said electrolyte being 80° C. to 130° C., the voltage between said anode and said cathode being 5 to 15 volts, and the anode current density 0.5 to 25 a./dm.².
- 55 8. In a process as set forth in claim 7, said voltage being 6 to 12 volts, and said current density 4 to 12 a./dm.².
